UNITED STATES PATENT OFFICE

2,240,408

ADJUSTABLE WINDOW SHADE BRACKET

Roderick A. McGonigal, Wheeling, W. Va.

Application November 20, 1940, Serial No. 366,473

3 Claims. (Cl. 248—271)

This invention relates to an improved adjustable window shade bracket, and more particularly to a construction of window shade bracket wherein, when a pair of said brackets are employed for mounting a window shade roller, either of the brackets may be readily adjusted relatively to a supporting plate which is attached to a window casement for adapting the pair of brackets to window shades and window shade rollers of different lengths.

Still another aim of the invention is to provide a construction of window shade bracket, adapted to be employed in pairs for mounting a window shade roller, and wherein the roller cannot be detached from the brackets without releasing and extending one or the other of the brackets to thereby prevent the roller from becoming accidentally detached.

Still another object of the invention is to provide novel wedge means for clamping the shank portion of the shade bracket relatively to the supporting plate on which it is slidably mounted for retaining the bracket in any one of a plurality of adjusted positions relatively to its supporting plate.

Other objects and advantages of the invention will hereinafter become more fully apparent from the following description of the drawing, which illustrates a preferred embodiment thereof, and wherein:

Figure 1 is a fragmentary front elevational view of the upper portion of a window casement shown equipped with a pair of window shade brackets constructed in accordance with the invention.

Figure 2 is an enlarged front elevational view of the bracket disposed at the right hand side of Figure 1.

Figure 3 is an end view in elevation of the same looking toward the device from the left hand end of Figure 2.

Figure 4 is an enlarged horizontal sectional view taken substantially along the plane of the line 4—4 of Figure 2, and

Figures 5 and 6 are enlarged vertical sectional views taken substantially along the planes of the lines 5—5 and 6—6, respectively, of Figure 2.

Referring more particularly to the drawing, wherein like reference characters designate like or corresponding parts throughout the different views, 10 designates generally an adjustable window shade bracket constructed in accordance with the invention, and including a shade bracket member 11 provided with an opening 12 for receiving a pin, not shown, which projects from the end of a shade roller, not shown. The

portion of the bracket 11 around the opening 12 is pressed outwardly, as best seen at 13 in Figures 2 and 4, to reduce the frictional engagement between the end of the roller and the outer side of the bracket 11. The opening 12 is shown as being circular, but it may be of any required shape to conform to the shape of the pin that it is to receive, and as in the case of pairs of conventional window shade brackets the adjustable shade brackets 10 will likewise be provided in pairs, as illustrated in Figure 1, and the opening 12 of the bracket member 11 of one of the adjustable shade brackets 10 will be circular whereas the opening 12 of the other will be polygonal shaped, or oblong, as in most instances, corresponding to the openings in conventional window shade brackets except that the oblong opening does not open outwardly of an edge of the bracket member, for a reason which will hereinafter become apparent. The bracket member 11 is provided with an elongated shank portion 14 which is disposed substantially at a right angle to the aforementioned portion of the member 11.

25 The adjustable shade bracket 10 also includes a supporting or base plate 15 which is provided with openings adjacent its side edges and intermediate of its ends, designated 16, for receiving fastenings 17 for securing the plate 15 to the 30 top rail of a window casement 18 adjacent one end and longitudinally thereof. The plate 15 is provided with transverse slots, extending to adjacent its side edges, and one of which is disposed adjacent each end thereof. The portions 35 19 of the plate 15, which are disposed beyond said slots, designated 20, are pressed outwardly to form outwardly offset guide portions. The shank 14 extends loosely beneath the guide portions 19 and over the intermediate portion 21 40 of the plate 15 and is thereby slidably mounted longitudinally of the plate 15 for slidably supporting the bracket member 11 relatively to the plate 15 and to the top rail of the casement 18.

A lever 22 is pivotally connected at one end 45 by means of a rivet or other pivot means 23 to the plate 15, adjacent its upper edge. As best seen in Figures 5 and 6, the rivet or pivot member 23 is countersunk in the back of the plate 15 so that it is disposed flush with the back portion 50 thereof and so that the portion of the plate 15 which engages against the casement 18 will provide a smooth, flat surface. The lever 22, when disposed in a depending, perpendicular position will be disposed with one of its longitudinal edges 55 engaging against the inner edge of the inner-

most guide portion 19, as best seen in Figure 2. A tapered lug 24 projects from said aforementioned edge of the lever 22 and is adapted to be disposed between the inner side of the innermost offset portion 19 and the outer side of a portion of the shank 14 to provide a wedge for clamping the shank 14 relatively to the plate 15 and particularly to the intermediate portion 21 thereof. A knob 25 is attached to and projects outwardly from the lower, free end of the lever 22 and provides a finger hold for swinging the lever upwardly and outwardly relatively to the plate 15 for releasing the shank 14 or in the opposite direction for positioning the lever in the position, as seen in the drawing, for clamping the shank 14 to the plate 15.

As best seen in Figure 1, the adjustable window shade brackets are adapted to be mounted in pairs, one adjacent each end of the upper rail of a window casement, such as shown at 18 in Figure 1, with the bracket members 11 projecting outwardly from the inner side of the casement 18, substantially at right angles to their shank portions 14 which are disposed substantially parallel to the casement 18. The members 11 likewise are disposed to form the adjacent ends of the adjustable window shade brackets 10 and are adjustable relatively to one another for accommodating the pair of brackets 10 to window shades and rollers of different lengths. As previously mentioned, the opening 12 of one of the bracket members 11 will be circular while that of the other will be oblong or polygonal shaped, and by swinging the levers 22 outwardly and upwardly, the shank portions 14 will be released so that the members 11 may be extended relatively to each other to permit the shade roller to be disposed therebetween and to permit the pins at the ends thereof to be inserted in the openings 12. The members 11 may then be adjusted simultaneously relatively to their supporting plates 15 for centering the roller and shade, not shown, relatively to the side rails of the casement 18, after which the levers 22 are swung downwardly and inwardly to position the wedge members 24 for clamping the shanks 14 in the plates 15. It will be obvious that the wedge members 24 will prevent the members 11 from moving relatively to the plates 15 while they are in clamping positions, as illustrated in Figures 4 and 6, to thereby positively prevent the shade roller from being released without releasing the wedge members 24. The wedge members 24 will prevent either inward or outward movement of the shanks 14 relatively to the plates 15 and when the shade roller is disposed between the members 11 it will of course, likewise prevent the shanks 14 from moving inwardly of one another. It will be readily apparent that a pair of adjustable window shade brackets 10 when mounted, as illustrated in Fig-

ure 1, will provide means for mounting shade rollers of a wide variety of lengths without removing either of the supporting plates 15 from the casement 18 and will at the same time permit shade rollers and shades of any of the various sizes to be correctly centered relatively to the side rails of the casement 18.

If desired, the window shade brackets 10, as shown in Figure 1, can be reversed so that the shade bracket members 11 will form the remote ends thereof to thereby position the other portions thereof beneath the shade and roller. When so arranged, it will be necessary that the portions 13 project from the inner sides of the members 11, instead of from the outer sides thereof, as illustrated, so that said portions 13 will extend toward the ends of the shade roller.

Various modifications and changes are contemplated and may obviously be resorted to as only a preferred embodiment of the invention has been disclosed.

I claim as my invention:

1. A window shade bracket comprising a bracket having an elongated shank portion disposed at an angle thereto, a supporting plate, said supporting plate being provided with a guide in which said shank portion is slidably mounted, a lever pivotally connected at one end to the supporting plate, and a wedge shaped lug projecting laterally from one edge of said lever and removably disposed between the guideway and shank for clamping the shank in the guideway.

2. An adjustable window shade bracket comprising a shade bracket having an elongated angularly disposed shank, a supporting plate having an outwardly offset portion through which the shank extends and in which the shank is slidably mounted longitudinally of the plate, and a wedge member pivotally mounted on the plate and having a portion removably mounted between said outwardly offset portion and shank for clamping the shank to the supporting plate.

3. An adjustable window shade bracket comprising a shade bracket having an elongated shank disposed substantially at a right angle thereto, a base plate, adapted to be secured to a window casement and disposed horizontally thereof, said base plate having slotted, outwardly offset end portions for slidably receiving said shank for slidably mounting the shade bracket longitudinally of the base plate, a lever pivotally connected at one end to said base plate, adjacent the upper edge thereof and depending downwardly therefrom and disposed adjacent the inner edge of the inner outwardly offset portion, and a wedge shaped lug projecting from one edge of said lever and removably disposed between said innermost outwardly offset portion and shank for detachably clamping the shank to the base plate.

RODERICK A. McGONIGAL.
